F. COATES

AUTOMATIC CARTON MOUTH COATING MACHINE

Filed Aug. 11, 1921

UNITED STATES PATENT OFFICE.

FREDERICK COATES, OF CINCINNATI, OHIO, ASSIGNOR TO FEDERAL PRODUCTS COMPANY, OF CINCINNATI, OHIO, A CORPORATION OF OHIO.

AUTOMATIC CARTON-MOUTH-COATING MACHINE.

Application filed August 11, 1921. Serial No. 491,452.

To all whom it may concern:

Be it known that FREDERICK COATES, a citizen of the United States, residing at Cincinnati, in the county of Hamilton and 5 State of Ohio, has invented certain new and useful Improvements in Automatic Carton-Mouth-Coating Machines, of which the following is a specification.

This invention relates to machines for 10 manufacturing paper cans or cartons.

More particularly the invention relates to a machine for coating the mouths of paper cans or cartons as for instance with water 15 proofing material.

In the manufacture of paper cans it is 20 desirable frequently that the inner wall of the can mouth shall be thoroughly coated with a waterproofing substance while leaving the outer wall uncoated so that an adhesive may be applied thereto and will stick without interference from the waterproofing coating. It follows, therefore, 25 that the usual method of coating the lips or mouths of cartons by dipping the same in a waterproofing solution is defective in that both the inside and the outside of the mouth are coated and consequently adhesive applied to the outside does not properly adhere to the material of the carton since the pores 30 have been filled by the waterproofing.

One very important object of the present invention is to provide means whereby the inside of the carton mouth may be thoroughly and efficiently coated with waterproofing 35 material without any of said waterproofing getting on the outside of the carton.

It is of course possible to waterproof the inside of a carton mouth by applying the waterproofing with a brush or the like but 40 this naturally is a waste of time and is a very expensive procedure on account of the labor costs.

A second important object of the invention 45 is to provide an improved machine for coating the inside of carton mouths which are operated in an entirely automatic manner and wherein the handling of the cartons will be reduced to a minimum.

With the above and other objects in view, 50 the invention consists in general of certain novel details of construction and combinations of parts hereinafter fully described, illustrated in the accompanying drawings, and specifically claimed.

In the accompanying drawings, like characters of reference indicate like parts in the several views, and:

Figure 1 is a side elevation partly in section of a machine constructed in accordance with this invention.

Figure 2 is an enlarged detail section through one of the carton holders and the adjacent parts.

Figure 3 is a detail section partly broken away on the line 3—3 of Figure 1.

Figure 4 is a detail view showing a portion of a certain supply channel and partition used herewith.

In the embodiment of the invention herein illustrated there is provided a stand 10 from 70 which extends upwardly a standard 11 having at its upper end an arm 12 extending forwardly over the stand. Depending from the arm 12 is a bearing 13 and a similar bearing 14 is formed on the standard 11 in alignment with the bearing 13. Through the bearings 13 and 14 passes a shaft 15 carrying on its outer end a driving pulley 16 and an idler pulley 17. At the forward end of the arm 12 there is provided a bearing 18 and journaled on this bearing is a vertical shaft 19 whereon is fixed a bevel gear 20 meshing with a bevel gear 21 fixed on the shaft 15. This shaft 19 has keyed to its lower end a forearmed spider 22 and 85 resting on top of this spider is a hub 23 which is journaled on the shaft 19 and which is provided at its upper end with a belt pulley 24. On the shaft 15 is also a belt pulley 25 and trained over the pulleys 24 and 25 is a belt 26 which is lead around idlers 27 as shown in Figure 1. At the ends of the arms of the spider 22 are vertical bearing bosses 28 through which extend shafts 29 carrying on their upper ends 90 pinions 30 which mesh with a gear 31 on the sleeve 23. It is to be observed that the belt 26 is a straight belt so that the gear 31 will revolve in one direction while the spider 22 turns in the opposite direction. By this means the spider is rotated about 95 its axis while at the same time the shafts 29 are rapidly rotated in the opposite direction about their axes. The shaft 29 is hollow and fitted loosely therein is a pipe 100 32 which extends up through a drip pan 33 secured to the bearing 28 by a bracket 34. On the upper end of this shaft 29 is mount-

ed a head 35 having carton gripping fingers 36 arranged around its periphery so that a carton C can be inverted and placed between these fingers. The head 35 is recessed as at 37 and from this recess waste passages 38 extend through the bottom of the head and communicate with an escape spout 39 in the bottom of the drip pan 33, the passages 38 being brought into registry 10 one after the other with this spout as the head rotates. Fixed on the base 10 is a tank 40 and within this tank is mounted a circular plate or runner 41 having one part depressed and channeled to form a trough 42 wherewith communicates a supply pipe 43 having in turn connection to a suitable source of supply for the coating which is to be applied to the carton. On the lower end of the shaft 19 is a wheel 44 having 15 its rim channeled on the under side as at 45 and the lower ends of the pipes 32 communicate with this channel. The pipes 32 are each closed at its upper end and leading from this upper end to points adjacent the 20 carton wall are distributor pipes 45. It is to be understood that the coating is forced through the pipe 43 under pressure and it is also to be understood that the channel 45 is divided into several segments corresponding 25 to the number of carton holders such division being accomplished by means of partitions 47. In operation the attendant is positioned in front of the machine which is the position in the left of Figure 1. A suitable supply of uncoated cartons are provided 30 and the machine is started in motion. This causes the carton supporting head to be brought around in front of the operator one after the other. The operator takes a 35 carton in inverted position and places it in the head. As the head travels around the coating mixture is forced up through the pipe 32 and distributor nozzles 46 and is ejected from the ends of these nozzles on 40 to the inside mouth of the carton. Since the carton is in rapid revolution with respect to these distributor nozzles a uniform coating will be supplied all around the nozzles and any excess will run down into the recess 45 37 and thence through the passages 38 and 39 into the tank 40 from whence it may be drawn off by a drain pipe 48 and lead to the source of supply to be pumped back again. As the coated carton comes around 50 to the operating station the operator grips the same and quickly removes it with one hand while with the other hand the uncoated carton is placed in the holder.

Of course this operation is repeated as long as the machine is running.

There has thus been provided a simple and efficient device of the kind described and for the purpose specified.

It is obvious that minor changes may be 55 made in the form and construction of the

invention without departing from the material principles thereof. It is not therefore desired to confine the invention to the exact form herein shown and described, but it is wished to include all such as properly come 70 within the scope claimed.

Having thus described the invention, what is claimed as new is:—

1. In a carton coating machine, a carton carrier, an arm supporting said carrier, a shaft to which said arm is fixed, means to drive said shaft and move the carrier around a circular path, means to rotate the carrier during its movement along its path, a source of supply for coating material, a delivery 75 nozzle supported to rotate with the carrier and deliver coating material to a carton on said carrier, a coating material receiving pocket whereto said nozzle is connected, said pocket being opened at the bottom and rotating with the carrier, a circular plate whereon said pocket rests and travels, said plate having a trough forming around a portion wherewith said pocket may register during 80 its movement, said trough having permanent connection with the source of supply, and means to receive excess coating material delivered through said nozzle. 85

2. In a carton coating machine, a main shaft, a spider carried by said shaft, a sleeve on said shaft, bearings at the ends of the spider arms, carton carriers provided with shafts mounted in said bearings, gears on said shafts, a gear on said sleeve meshing with said first mentioned gears, means to 95 drive said shaft and spider and thereby cause rotation of the carriers about their respective axes and means to coat the mouths of the cartons during their revolution.

3. In a carton coating machine, a main 105 shaft, a spider carried by said shaft, a sleeve on said shaft, bearings at the ends of the spider arms, carton carriers provided with shafts mounted in said bearings, gears on said shafts, a gear on said sleeve meshing with said first mentioned gears, means to drive said shaft and spider and thereby cause rotation of the carriers about their respective axes, other means to rotate said sleeve and its gear in a direction opposite 110 to the rotation of said spider and means to coat the mouths of the cartons during their revolution. 115

4. In a carton coating machine, a main shaft, a spider carried by said shaft, a 120 sleeve on said shaft, bearings at the ends of the spider arms, carton carriers provided with shafts mounted in said bearings, gears on said shafts, a gear on said sleeve meshing with said first mentioned gears, means to 125 drive said shaft and spider and thereby cause rotation of the carriers about their respective axes, other means to rotate said sleeve and its gear in a direction opposite to the rotation of said spider, a circular 130

plate surrounding said shaft and having one portion formed as an open topped trough, a disk carried by said shaft and having portions of its rim formed as open bottomed pockets, said disk resting on said plate whereby said pocket intermittently registers with said trough, a source of supply for coating material connected to the trough, a pipe leading from each of the pockets upward through the carton carrier shaft, and a ¹⁰ nozzle leading from the upper end of each pipe.

In testimony whereof I affix my signature.
FREDERICK COATES.
